UNITED STATES PATENT OFFICE.

RICHARD SELIGMAN, OF SEATTLE, WASHINGTON.

BUTTON.

1,319,908.

Specification of Letters Patent. Patented Oct. 28, 1919.

Application filed June 5, 1919. Serial No. 302,017.

To all whom it may concern:

Be it known that I, RICHARD SELIGMAN, a citizen of the United States, and resident of Seattle, in the county of King and State 5 of Washington, have invented certain new and useful Improvements in Buttons, of which the following is a specification.

This invention relates to buttons of the so-called lever-head type and is an improvement on my Patent No. 1,230,804; dated 10 June 19, 1917.

My present invention has for its object in addition to providing a head connected to a post by a double hinged member where- 15 by it may be extended into substantial alinement with the post, to provide a spring acting upon each of the hinged portions for automatically completing the latter portion of the throw of the parts after having been 20 moved the first portion of its stroke by hand.

A further object of the invention is to so arrange the springs at these hinge joints that the parts will be releasably retained either when in extended, or when in folded 25 position.

With these and other objects in view, the invention consists of certain novel features of construction, as will be more fully described, and particularly pointed out in the 30 appended claims.

In the accompanying drawings:

Figure 1— is a sectional side elevation showing the button with its head in folded or closed position.

Fig. 2— is the same as Fig. 1 but showing the parts in extended position, the head being in substantial alinement with the post.

Fig. 3— shows the special form of the end of the tubular post after having been 40 flattened and cut into the desired shape.

Fig. 4— is a side elevation of the post, showing the formation of the hinge structure at the end thereof.

Fig. 5— is a front elevation illustrating 45 the hinged structure and showing the spring tongue at the back and the fulcrumed bar at the front of the hinge portion of the post.

Fig. 6— is a perspective view of the connector member.

Fig. 7— is a side elevation of this member.

Fig. 8— is a transverse section through 55 the head showing the connector member hinged in the inner plate of the movable head.

Referring to the drawings, 10 designates the post of the button, which is preferably drawn up into tubular form from the flat plate 11, but which may be made in any 60 suitable shape and onto which plate may be rolled the usual gold front 12 if desired.

The free end of this post may be constructed into any suitable shape to form a hinge to receive the connector member 65 13, presently described, but I preferably flatten this end into substantially the shape best illustrated in Fig. 3 in which a stop bar 14 is formed across the end, a portion of the stock at the center being cut out at 70 15 leaving a spring tongue 17. The side portions 18 are then bent over as illustrated in Fig. 4 forming an eye 29, the cross bar 14 extending down in front of the eye serving as a stop or rest to limit the downward 75 movement of the connector member 13.

This connector member 13 is preferably formed with a body portion, one end of which is provided with a cross bar 19 forming a T-shaped head thereon. This cross bar 80 provides trunnions over which the members 18 are bent forming a hinge joint in which the connector swings. The spring tongue 17 is arranged to exert a pressure 85 against the flattened portion 20 at the back or the flattened portion 21 at the side of the cross bar thus serving to releasably retain the connector member either when in horizontal or when in vertical position relative to the axis of the post.

The opposite end of this connector member is also provided with a T-head or cross bars 22, the ends of which form a hinge by being retained in suitable depressions 23 in the back plate 24 of the movable head 25 and I have also provided a pair of diverging horns 26 and 27 on the free end of this connector member, which are set at an angle of substantially 45° each from the plane of the connector to be engaged by a spring 100 tongue 28 which is formed on the under side of the bottom plate 24 to press the cross bars 22 into their recesses 23, these horns also serving under pressure of the spring 28 to yieldably retain the head 25 either in 105 a folded, or in extended position relative to the connector member.

My improved button is very simple, practical, and inexpensive in construction and by the use of my particular form of hinge construction the head may be extended into 110 substantial alinement with the axis of the

post, or it may be folded into a plane at substantially a right angle to the plane of the post, and after having been moved by hand part way either toward or from closed 5 position, the springs at the hinge joints act upon the members to automatically complete the last end of the opening or closing stroke and also serve to releasably retain the members either in extended or in folded 10 position.

Any style of ornamented front plate may be attached to the back plates of either of the button heads, but I have shown them connected by rolling the edges of one over 15 those of the other.

A button of my improved construction has many advantages over the usual lever type of button among others being: First, when the head is extended in line with the 20 post as illustrated in Fig. 2, it may be readily passed through the button holes of a stiffly starched collar or cuff and that without enlarging the button holes which is not the case where a large ball or bean end 25 is used or when a head of the flat-rigid type is employed; second, a button of my improved type may have both heads large enough to absolutely prevent any possibility of being drawn through the unstarched button 30 holes of a soft cuff; third, the extendible head may serve the purpose of a lever to draw together and ends of a collar, upon being passed through the button holes thereof. 35 It is found in practice that the ordinary lever button head in being turned up in line with the post that a portion of the head lies back against the side of the post, thereby requiring additional length of post to operate it, but by the use of my improved construction of button head, no part of the head is folded back upon the side of the 40

post, therefore the length of the post may be reduced to the minimum.

The foregoing description is directed 45 solely toward the construction illustrated, but I desire it to be understood that I reserve the privilege of resorting to all the mechanical changes to which the device is susceptible, the invention being defined and 50 limited only by the terms of the appended claims.

I claim:

1. A button comprising a post, a member hinged to said post, a head hinged to said member whereby both may be extended substantially in line with said post, and a spring acting upon said hinges to automatically complete the latter portion of an operating movement of the parts after an initial manual movement thereof. 55

2. A button comprising a post, a member hinged to said post, a head hinged to said member whereby both may be extended substantially in line with said post, a spring 65 acting upon said hinges to automatically complete the latter portion of an operating movement of the parts after an initial manual movement thereof, and also serve to yieldably retain the parts in adjusted position. 70

3. A button comprising a head having a fixed post, an extension member hinged to said post, a head hinged to the free end of said member whereby both may be extended substantially in line with said post, a spring 75 in said head acting upon the free end of said member and arranged to assist in completing a relative movement between said extension and head, said spring also serving to yieldably retain said posts in adjusted position. 80

In testimony whereof I affix my signature.
RICHARD SELIGMAN.
